UNITED STATES PATENT OFFICE.

EUGENE VON VARGYAS AND JOSEPH W. DEIDRICK, OF PITTSBURGH, PENNSYLVANIA.

COLLAPSIBLE DRINKING-CUP.

1,025,937.

Specification of Letters Patent.

Patented May 7, 1912.

Application filed July 24, 1911. Serial No. 640,221.

To all whom it may concern:

Be it known that we, (1) EUGENE VON VARGYAS and (2) JOSEPH W. DEIDRICK, (1) a subject of the King of Hungary and (2) 5 a citizen of the United States of America, residing at Pittsburgh, in the county of Allegheny and State of Pennsylvania, have invented certain new and useful Improvements in Collapsible Drinking-Cups, of 10 which the following is a specification, reference being had therein to the accompanying drawing.

This invention relates to collapsible drinking cups of that type disclosed in our companion application, and besides having the same objects in view, the present invention aims to provide a cup that is made of a blank and maintained in a folded position without resorting to the use of staples or 20 other fastening means.

Another object of this invention is to provide a one piece drinking cup having foldable edges that form a non-leakable receptacle.

25 With the above and other objects in view, the invention resides in the novel construction to be hereinafter specifically described and then claimed, and reference will now be had to the drawing, wherein:

30 Figure 1 is a plan of a blank from which the cup is made, Fig. 2 is a similar view showing the blank partially folded, Fig. 3 is a similar view showing the flaps of the blank folded, Fig. 4 is a similar view showing a further folding of the flaps, Fig. 5 is a similar view of a cup, and Fig. 6 is an enlarged view of the upper edge of the cup.

The blank from which the cup is made comprises two sections 1 and 2 adapted to 40 be folded one upon the other on the dot and dash line 3. Each section has angularly disposed edges 4 and a curved outer edge 5, the curved outer edge 5 of the section 2 being cut away intermediate the ends thereof, as at 6 to facilitate opening the walls of the receptacle formed by said sections.

45 After the section 2 is folded upon the section 1, the angularly disposed edges of said

sections are folded upon the dot and dash line 7, thereby providing flaps 8. The 50 flaps 8 have the confronting edges thereof folded upon the dot and dash lines 9 to provide auxiliary flaps 10, and then the main flaps 8 are again folded upon the dot and dash lines 11, whereby the auxiliary 55 flaps 10 will be folded inwardly against the main flaps, with the fold of the auxiliary flaps in parallelism with the fold of the main flaps. This folding of the flaps 8 is clearly shown in Figs. 3 to 5 inclusive and 60 with the flaps approximately the same length as the sections of the receptacle, non-leakable connections are made between the two sections of the receptacle.

The drinking cup can be made of light and 65 durable waterproof paper, paperoid or other material and in actual practice the cup will hold water or other liquid for drinking purposes.

By pressing the folded edges of the cup 70 toward each other by the thumb and fingers, the walls of the receptacle formed by the sections 1 and 2 are open at the upper ends whereby water can be easily collected in the cup. The manner of folding the edges of 75 the sections 1 and 2 obviates the necessity of using any fastening means.

What we claim is:—

A drinking cup in substantially flat form and made from a single blank consisting of 80 two similar parts integral with each other and adapted to be folded upon each other along the middle edge of the blank, each of said parts being formed with flaps which extend lengthwise along its side edges and 85 which flaps are twice folded longitudinally and in the finished cup are interlocked and lie on one side of the finished cup outside the latter.

In testimony whereof we affix our signatures in the presence of two witnesses.

EUGENE VON VARGYAS.
JOSEPH W. DEIDRICK.
